UNITED STATES PATENT OFFICE.

FRANCIS E. LIGER, OF LAINGSBURG, MICHIGAN, ASSIGNOR TO EUGENE L. LIGER, OF CINCINNATI, OHIO.

VEHICLE-CURTAIN.

1,159,321.

Specification of Letters Patent.

Patented Nov. 2, 1915.

Application filed August 14, 1914. Serial No. 856,743.

To all whom it may concern:

Be it known that I, FRANCIS E. LIGER, a citizen of the United States, and residing at Laingsburg, in the county of Shiawassee 5 and State of Michigan, have invented a new and useful Improvement in Vehicle-Curtains, of which the following specification is a full disclosure.

My invention relates to side curtain supports for buggies or other vehicle tops or coverings and has for an object a means non-expansible for reinforcing a margin of the curtain, primarily that from which it is suspended, to avoid sagging or flaring when 10 in use, whereby the material is relieved of wearing strains, and of assistance in withdrawing the curtain from its support. It is also foldable with the curtain.

A further object of the invention is to 20 secure a metallic binding, comprising rectangular links hingedly united to form a chain structure, within a margin lap fold of the curtain, providing a reinforced hem, with fastening eyelets through the hem and 25 within respective links.

Further objects and advantages of the invention will be more readily apparent from the annexed drawings illustrating a preferred embodiment and from the following 30 description thereof, and in such drawings, like characters of reference denote corresponding parts throughout the several views of which:

Figure 1 is a plan view of a side curtain 35 of a buggy partly mutilated to more clearly show the chain or link binding. Fig. 2 is an enlarged detail plan view of two links hingedly united of which the chain binding is comprised.

The supporter consists of a plurality of 40 links 1 successively connected by a strap 2 bent tubularly around opposite cross-bars of the links adjacently disposed to hingedly successively connect a plurality of links 45 into a chain length. The links preferably are rectangularly bent strands of wire to provide a comparatively thin and wide chain binding so that when it is secured within the hem or to the margin of the curtain 50 it will not have a bulky appearance, or be excessive in weight.

The design, it is obvious, may be variously modified within the contemplation of the invention, which from a generic aspect

may be defined as a metallic successively connected and foldable link binding, and certain links thereof each preferably of a contour to surround or interveningly receive a curtain fastening eyelet secured to the material at the binding margin or the 60 links themselves may serve as fastening eyelets.

The curtain 3 herein illustrated represents the side curtain of a buggy of the customary outline with the binding within a hem 65 margin 4 representing the upper edge of the curtain when in use. The hem margin 4 consists of the ordinary lap fold with the link binding 5 longitudinally secured within the hem by lines of stitches 6 and 7 70 through the curtain material along both longitudinal edges of the link binding, and by the end stitches 8 at both ends thereof.

A plurality of fastening eyelets 9 are secured through the hem margin and within 75 respective links of the binding for buttoning the curtain in the well-known manner to buttons projected from the buggy top frame. Such location of fastening eyelets will preclude any pulling or tearing of the 80 eyelets out of the curtain, and the link binding offers a freer release of the eyelets from the buttons in withdrawing the curtain under the general abusive practice of pulling from one end of the curtain outward. The 85 eyelets or the fastening elements it is obvious may be otherwise located although in the position shown the binding offers and serves a two-fold purpose. With the link 90 or chain binding embedded within the hem margin of the curtain it is concealed and does not detract in any degree from the ornamental or finished appearance of the curtain. It being non-flexible or non-expansible 95 rigidly supports the curtain in position against sagging or flaring and presents no detriment in compactly folding the curtain when not in use. The binding reinforces the margin to prevent violent vibration of the curtain and thus eliminates the noise incident thereto.

As a curtain supporter, the binding is only supplied to the upper margin but its use may be extended to the side or base margin and its adaptation for marginally binding or webbing a covering for various other and analogous uses is evident.

Having described my invention, I claim

as new and desire to secure by Letters Patent of the United States:—

1. The combination of a vehicle curtain having a hem margin from which the curtain is suspended, a binding inclosed within said margin comprising a plurality of hingedly connected links, and fastening eyelets secured through the curtain margin and each interveningly bounded by a respective link.

2. In an article of the class described, a pliable cover member, a binding therefor comprising a plurality of non-pliable ring elements hingedly connected, secured to a margin of said cover and foldable therewith.

3. In an article of the class described, a pliable cover member, a margin binding therefor, comprising a plurality of non-pliable ring elements hingedly connected and secured to a margin of said cover member and foldable therewith, and fastening elements secured to said cover member each within a respective ring element. 20

In witness whereof, I hereunto subscribe 25 my name, as attested by the two subscribing witnesses.

FRANCIS E. X. LIGER.
